UNITED STATES PATENT OFFICE.

WILLIAM TIMM, OF LOST NATION, IOWA.

CLAMPING DEVICE.

1,176,874.

Specification of Letters Patent. Patented Mar. 28, 1916.

Application filed August 14, 1911. Serial No. 643,993.

To all whom it may concern:

Be it known that I, WILLIAM TIMM, a citizen of the United States, residing at Lost Nation, in the county of Clinton and State 5 of Iowa, have invented a new and useful Clamping Device, of which the following is a specification.

This invention relates to improvements in clamping devices, and the primary object 10 of the invention is the provision of a clamp adapted to properly support the panels to posts and the like in the construction of hay racks, gates and fences, this particular form 15 of clamping device being provided with a main body portion adapted to pass upon the outside of the panel and provided with a pair of right angled spaced arms adapted to straddle the post or supporting portion to which the panel is to be secured and be held 20 there against by means of clamping plates, the terminals being threaded for the reception of nuts whereby the said clamping plates are actuated to clamp, and the supporting device holds the panel to the post.

25 A further object of this invention is the provision of a clamping device having a series of terminals which so grip the panel and post as to prevent the panel turning and at all times retain said panel in a position at 30 right angles to the post to which it is to be secured, and at the same time dispense with the use of nails and bolts in securing the panels in place.

With the foregoing and other objects in 35 view which will appear as the description proceeds, the invention resides in the combination and arrangement of parts and in the details of construction hereinafter described and claimed, it being understood 40 that changes in the precise embodiment of invention herein disclosed can be made within the scope of what is claimed without departing from the spirit of the invention.

In the drawings—Figure 1 is a side elevation of the clamping device in use showing a panel clamped to and supported by a post. Fig. 2 is a top plan view thereof. Fig. 3 is a front elevation thereof. Fig. 4 is a rear elevation thereof.

50 Referring to the drawings, A designates a post which is rectangular in cross section, and B a panel which is of lesser thickness and in this case may represent the panel of a fence, the same being secured to the post 55 by means of the clamping device, which consists of the central bar 1, having the series

of four right angled ends 2, 3, 4 and 5 arranged in pairs at opposite ends thereof and separated by the curved slots 6 and 7 respectively, as clearly shown in Fig. 3. Each 60 one of these respective arms are bent at right angles to meet each other and terminate in the cylindrical bolts or straddling terminals 8, 9, 10 and 11 respectively, their outer free ends being threaded for the reception of the 65 respective clamping plates 12 and 13, and the nuts 14 locking the said plates so as to draw the bar 1 closely upon the outer face of the panel B, the terminals straddling the fence post A while the portion of the said 70 terminals adjacent to the bar 1 contacts the panel B as at a, thereby providing means to prevent any twisting or torsion of the panel B within the clamping device.

By providing each one of the terminals 75 with the peculiar bends at their connections or junctions with the bar 1, it will be seen that the same will properly abut the upper and lower faces of the panel B and at the same time is fast upon and straddles the 80 post A, thus providing a means which will retain the panel securely against the fence post A and at the same time provide a receptacle at the junction of the terminals in the bar 1 which at all times retains the panel B 85 at right angles to the fence post A and thus prevent slipping or torsion of the same thereon which might tend to loosen the clamp or distort the panel.

Although the clamping device has been 90 illustrated as in operation upon a fence post and panel, it is evident that the same may be used wherever it is desired to place transverse strips in making many forms of racks, for instance hog racks and hay racks, and 95 the construction of gates, this device dispensing with nails and bolts and not splitting or fraying the wood of the posts and panels.

Because the bar 1 is provided within its 100 ends with the notches 6 and 7 which are closed together as shown at 50, a cold chisel may be inserted into the notches 6 and 7, thereby to widen out the space between the arms, and to permit the arms to coöperate 105 with posts of varied widths. This operation also causes the arms to move vertically toward each other, thereby causing the arms to grip the upper and lower edges of the panel.

What is claimed is:

110 The combination with a panel and a post located upon one side of the panel and ex-

tended transversely of the panel, of a bar located upon the other side of the panel and extended transversely of the panel and engaging the panel, the bar terminating at its opposite ends in spaced pairs of arms, the arms of the pairs extending across the edges of the panel and lying on opposite sides of the post; separate plates through which the arms of the pairs pass, the plates engaging 10 the rear face of the post; and fastening devices on the arms and engaging the plates; the ends of the bar being provided with V-shaped chisel-receiving notches defined by the arms of the pairs, and the bar being 15 split and closed together at the points of the

notches to permit an adjustment of the spacing of the arms of the pairs, thereby to accommodate posts of different sizes and to secure a binding of the arms upon the opposite edges of the panel.

20

In testimony that I claim the foregoing as my own, I have hereto affixed my signature in the presence of two witnesses.

WILLIAM ^{his} X TIMM.
